UNITED STATES PATENT OFFICE.

HAROLD O. HOLTE, OF PITTSBURGH, PENNSYLVANIA; HALVOR HOLTE, SPECIAL ADMINISTRATOR OF SAID HAROLD O. HOLTE, DECEASED, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed March 19, 1926. Serial No. 95,923.

My invention relates to railway traffic controlling apparatus, and particularly to apparatus of the type comprising train-carried governing means controlled by energy received from the trackway.

I will describe one form of railway traffic controlling apparatus embodying my invention, and will then point out the novel features thereof in claims.

10 In the accompanying drawings, Fig. 1 is a diagrammatic view illustrating one form of railway traffic controlling apparatus embodying my invention. Fig. 2 is a view showing, in perspective, a portion of the 15 train-carried apparatus shown in Fig. 1.

Similar reference characters refer to similar parts in both views.

Referring first to Fig. 1, the reference characters 1 and 1^a designate the track rails of a stretch of railway track over which traffic normally moves in the direction indicated by the arrow. These rails are divided, by means of insulated joints 2, to form a plurality of track sections, only one of 25 which, A—B, is illustrated in the drawing. As shown in the drawing, each track section is provided with a trackway signal which is controlled in accordance with traffic conditions by means forming no part of my 30 present invention and omitted from the drawing for the sake of simplicity. These signals may be of any suitable form and are here shown as semaphore signals each designated by the reference character S with an 35 exponent corresponding to the location and each capable of displaying a proceed, a caution, or a stop indication. Associated with signal S^b, are two circuit controllers C and D. Circuit controller C comprises a movable lever 7 and circuit controller D comprises a movable lever 10, the levers 7 and 10 being controlled by signal S^b to swing into engagement with selected ones of fixed contacts associated therewith in accordance 45 with the position of the signal, as will be clear from the drawing.

Train controlling current is at times supplied to the rails of section A—B by a track transformer T. The primary 4 of this transformer is constantly supplied with alternating current from secondary 5 of a line transformer L, the primary 6 of which is

supplied with alternating current from an alternator M.

Associated with transformer T is a slow 55 releasing relay R. This relay is provided with a circuit over which current flows from secondary 5 of transformer L, through wires 70 and 71, contact 7—8 of circuit controller C, wire 72, back contact 14 of relay R, wire 60 73, winding of relay R and wires 74 and 75 back to secondary 5 of transformer L. This circuit is closed only when signal S^b indicates caution or proceed, under which condition current will be supplied to relay R 65 over its own back contact. The relay therefore becomes energized but this energization of the relay opens back contact 14 thereof, so that the circuit just traced for the relay is interrupted. After a time interval 70 due to the slow releasing characteristic of the relay, the back contact 14 again closes and current is again supplied to the relay. It follows that as long as signal S^b indicates caution or proceed, relay R is operated intermittently. Due to the slow releasing characteristic of the relay the front contact 18—18^a is closed for a longer interval of time than back contact 18—18^b during each complete 75 cycle of operation of the relay. To state 80 the matter in another way, the front contact 18—18^a is closed for a greater proportion of a given interval of time than is back contact 18—18^b. When signal S^b indicates stop, circuit controller C is open and relay R 85 is continuously de-energized.

The supply of train controlling current to the rails of section A—B by secondary 3 of transformer T is controlled by circuit controller D and by relay R. The left-hand terminal of secondary 3 of transformer T is constantly connected through wire 15 with rail 1^a of section A—B. The right-hand terminal of secondary 3 of transformer T is at times connected with rail 1 of the section 95 through wire 16, contact 10—11 of circuit controller D, wire 17, front contact 18—18^a of relay R, and wires 19 and 20. This circuit is closed only when signal S^b indicates proceed and when relay R is energized to close its front contact 18—18^a. 100 When signal S^b indicates caution, the right-hand terminal of secondary 3 of transformer T is connected through wire 16, contact

10—12 of circuit controller D, wire 21, back contact 18—18^b of relay R and wires 19 and 20 to rail 1 of section A—B. This circuit is closed only when signal S^b indicates caution and when relay R is de-energized. When signal S^b indicates proceed or caution, however, relay R is operated intermittently, as has been explained hereinbefore. It follows, therefore, that when either of the two circuits just traced is closed, current is supplied to the rails of section A—B in the form of code impulse combinations made up of impulses of energy separated by time intervals. The relative proportions of a given interval of time that alternating current is supplied to the track rails for the code impulse combination corresponding to the proceed and caution indications of signal S^b may be regulated by properly designing the relay R. For example, I will assume that a complete cycle of operation of relay R occupies one second and that front contact 18—18^a is closed for two-thirds of a second and back contact 18—18^b is closed for one-third of a second during each such complete cycle. When signal S^b indicates proceed, therefore, code impulse combinations are supplied to the trackway according to the proceed code which comprises impulses of energy each lasting for two-thirds of a second and separated by time intervals of one-third of a second. When signal S^b indicates caution, however, code impulse combinations are supplied to the trackway according to the caution code which comprises impulses of energy of one-third of a second duration separated by time intervals of two-thirds of a second.

When signal S^b displays a stop indication, relay R is continuously de-energized and the right-hand terminal of secondary 3 of transformer T is then connected directly with rail 1 of section A—B over wire 16, contact 10—13 of circuit controller D and wires 22 and 20. Under this condition therefore alternating current is supplied to the rails of section A—B without interruption.

It is understood that each of the remaining track sections is provided with apparatus similar to that just described for section A—B.

The reference character V indicates a train which is provided with receiving apparatus designated in general by the reference character W. This receiving apparatus comprises two magnetizable cores 23 and 23^a carried by the train in inductive relation with the two track rails 1 and 1^a respectively, and located in advance of the forward axle of the train. Core 23 is provided with a winding 24 and core 23^a is provided with a similar winding 24^a, the two windings 24 and 24^a being so connected in series that the voltage induced therein by alternating current flowing in opposite di-

rections in the two track rails at any instant are additive. The windings 24 and 24^a are connected through a suitable amplifier with the winding of a relay G.

It follows, therefore, that when alternating current is being supplied to the rails of section A—B from transformer T, relay G is energized and when this supply of current is interrupted, relay G becomes de-energized.

Relay G controls a second relay K which is illustrated in detail in Fig. 2. Referring to Fig. 2, relay K comprises two magnets designated in general by the reference characters K¹ and K². Magnet K¹ comprises two magnetizable cores 26 and 27, and this magnet is provided with a winding made up of two coils 26^a and 27^a located on the cores 26 and 27, respectively, and connected in series. In similar manner magnet K² comprises two magnetizable cores 28 and 29, provided with a winding made up of two coils 28^a and 29^a carried on cores 28 and 29, respectively, and also connected in series. Current is at times supplied, as will appear hereinafter, to the winding of magnet K¹, through wires 45 and 46, and at other times, current is supplied to the winding of magnet K² through wires 47 and 48. Each core of relay K is provided with a sleeve 30 of conducting material by means of which changes in the magnet flux in these cores are retarded. The magnets may therefore be termed "slow acting" magnets.

The reference character P¹ designates an armature in the form of a substantially flat plate of magnetizable material provided with pivots 31, 31 which are mounted in bearings not shown in the drawing, whereby the armature may swing about the axis of these pivots into engagement with the cores 26 and 27 of magnet K¹ or with the cores 28 and 29 of magnet K², depending upon which of these magnets attracts the armature more powerfully. The relay K comprises contacts controlled in accordance with the position occupied by armature P¹ so that when the armature is swung in one direction by magnet K¹, contact 40—40^a is closed, but that when the armature is swung in the opposite direction about axis 31 by magnet K², contact 40—40^b is closed.

Magnet K¹ also controls a second armature designated by the reference character P² and pivotally supported to swing about an axis 32. When magnet K¹ is de-energized armature P² drops down against a fixed stop 34 so that contact 37 is closed. When magnet K¹ is energized, however, armature P² is swung upwardly about its axis 32 toward the cores 26 and 27 of magnet K¹ to an upper position in which contact 36 is closed.

The reference character P³ designates a third armature which is controlled by magnet K² and is pivotally supported to swing about an axis 33. When magnet K² is de-

energized, armature P^3 drops, under the influence of gravity, to a lower position defined by a fixed stop 35, in which position a contact 39 is closed. When magnet K^2 is energized, however, armature P^3 is swung upwardly about axis 33 toward the cores 28 and 29 of magnet K^2 to an upper position in which contact 38 is closed.

Referring again to Fig. 1, when relay G is de-energized magnet K^1 of relay K is energized by current which flows from a suitable source of energy, such as a battery F, through wires 42 and 43, back contact 41-41^b of relay G, wire 45, coils 26^a and 27^a of relay K and wires 46 and 56 back to battery F. When relay G is energized, however, current flows from battery F, through wires 42 and 43, front contact 41-41^a of relay G, wire 47, coils 29^a and 28^a of relay K and wires 46 and 56 back to battery F. It will be manifest, therefore, that when relay G is energized, magnet K^2 of relay K is supplied with current and that when relay G is de-energized, magnet K^1 of relay K is supplied with current.

The relay K may be used to control train-carried governing means in any suitable manner, and as here shown this means comprises a plurality of governing devices such as electric lamps, 66, 67, 68 and 69. Lamp 66 is provided with a circuit over which current flows from battery F, through wires 42, 48 and 49, contact 36 operated by armature P^2 of relay K, wire 50, contact 38 operated by armature P^3 of relay K, wire 51, contact 40-40^b operated by armature P^1 of relay K, wire 52, lamp 66, and wires 53, 54, 55 and 56, back to battery F. This circuit is closed only when armatures P^2 and P^3 of relay K are both in their upper positions and armature P^1 of relay K is swung toward magnet K^2 , under which conditions lamp 66 is lighted. If armature P^1 is swung toward magnet K^1 and armatures P^2 and P^3 both occupy their upper positions, current flows from battery F, through wires 42, 48 and 49, contact 36 of relay K, wire 50, contact 38 of relay K, wire 51, contact 40-40^a of relay K, wire 57, lamp 67 and wires 58 and 56 back to battery F. Lamp 68 is provided with a circuit over which current flows from battery F, through wires 42, 48, 59 and 60, contact 37 of relay K, wire 61, lamp 68 and wires 62, 55 and 56 back to battery F. This circuit is closed only when armature P^2 of relay K occupies its lower position, under which condition lamp 68 is lighted. When armature P^3 of relay K occupies its lower position, current flows from battery F, through wires 42, 48, 59 and 63, contact 39 of relay K, wire 64, lamp 69, and wires 65, 54, 55 and 56 back to battery F, thereby lighting lamp 69.

As shown in the drawing, signal S^B is at proceed so that contact 7-8 of circuit con-

troller C is closed, with the result that relay R is intermittently operated. Contact 10-11 of circuit controller D is also closed and train controlling current is therefore supplied to the track rails from secondary 3 of transformer T over front contact 18-18^a of relay R. Under these conditions the proceed code is supplied to the trackway. Relay G is therefore alternately energized and de-

energized in such manner that it is energized for intervals of two-thirds of a second and is de-energized for intervals of one-third of a second. Each time relay G becomes energized the front contact 41-41^a of this relay becomes closed and magnet K^2 is energized, and each time relay G becomes de-energized, back contact 41-41^b of this relay becomes closed and magnet K^1 of relay K is energized. It follows that magnets K^1 and K^2 are alternately energized. When the current ceases to flow in the winding of one of the magnets K^1 or K^2 the magnetic field due to this current starts to collapse, but due to the conducting sleeves 30 on the cores an interval of time elapses before the flux dies out

completely in the cores of the magnet. Similarly, when the current commences to flow in the winding of the magnet, the magnetic field caused by this current grows gradually to its steady value but the growth of this field is retarded by the conducting sleeves 30 on the cores of the magnet. But when relay G is being supplied with a code impulse combination in accordance with the proceed code, magnet K^2 is energized for a greater proportion of a given interval of time than magnet K^1 , so that armature P^1 is swung toward magnet K^2 , thereby closing contact 40-40^b.

When armature P^1 is in its middle position the air gaps between the cores 28 and 29 of magnet K^2 and the armature P^1 are preferably smaller than the air gaps between this armature and the cores of magnet K^1 , so that the advantage of magnet K^2 is still further increased. The current which is intermittently supplied to magnet K^1 holds armature P^2 in its upper position, thereby opening back contact 37 and closing contact 36. In similar manner the intermittent energization of magnet K^2 holds armature P^3 in its upper position, thereby opening contact 39 and closing contact 38. As long as relay G is being energized in accordance with the proceed code, therefore, armatures P^2 and P^3 both occupy their upper positions and armature P^1 is swung toward magnet K^2 .

Armature P^1 remains in this position because the sleeves 30 on the magnet cores prevent sufficient decay of flux in magnet K^2 and sufficient increase of flux in magnet K^1 to swing armature P^1 to the left during the relatively short intervals in which magnet K^2 is de-energized and magnet K^1 is energized. Under these conditions the circuit for lamp 63 is closed and this lamp is light-

ed to indicate that the proceed code is being supplied to the train.

I will next assume that signal S^B indicates caution, so that contact 10—13 of circuit controller D is closed. Relay R is intermittently operated because contact 7—8 of circuit controller C is closed, and so the caution code is supplied to the rails of section A—B. Relay G is therefore intermittently energized, each period of energization being one-third of a second and each period of de-energization being two-thirds of a second. When relay G is energized, current is supplied to magnet K^2 of relay G, and the magnet K^1 of this relay is supplied with current when relay G is de-energized. It will be plain that when relay G is being supplied with the caution code, magnet K^1 is energized for a greater proportion of a given interval of time than magnet K^2 , so that the effect of magnet K^1 upon armature P^1 predominates over the effect of magnet K^2 on this armature and draws the armature toward magnet K^1 , thereby closing contact 40—40^a. Armature P^1 remains in this position during the supply of the caution code for the same reason that it remains in its opposite position during the supply of the proceed code. Armatures P^2 and P^3 are both held in their upper positions due to the intermittent energization of magnets K^1 and K^2 , respectively, so that contacts 36 and 38 are closed. When relay G is being supplied with the caution code, therefore, the circuit is closed for lamp 67, which becomes lighted.

I will now assume that signal S^B indicates stop so that contact 10—13 of circuit controller D is closed, thereby connecting secondary 3 of transformer T directly with the rails of section A—B. Uninterrupted alternating current is then supplied to the rails of section A—B and relay G is continuously energized. Current is therefore supplied continuously to magnet K^2 of relay K and armature P^3 is held in its upper position, but armature P^2 drops to its lower position against the stop 34. Armature P^1 is swung toward magnet K^2 , closing contact 40—40^b. The circuit for lamp 66 is now open at contact 36 but the circuit for lamp 68 is closed at contact 37 so that lamp 68 becomes lighted.

Should relay G become de-energized as by the presence of a train in section A—B ahead of train V, back contact 41—41^b of relay G would be continuously closed. Under this condition, magnet K^1 of relay K would be continuously energized, thereby swinging armature P^1 toward magnet K^1 and closing contact 40—40^a. Armature P^2 would be held in its upper position, but armature P^3 would drop, thereby opening the circuit for lamp 67 at contact 38. But with armature P^3 in its lower position, contact 39 would be closed so that lamp 69 would be lighted.

It will be plain therefore that the train-carried apparatus herein shown and described is selectively responsive to the presence and absence of alternating current, and is also selectively responsive to the code impulse combinations supplied thereto in accordance with the proportion of a given interval of time that current is supplied to the rails. One advantage of apparatus embodying my invention is that because the operation of relay K depends upon the relative duration of energization of the magnets K^1 and K^2 a considerable variation in the durations of these intervals may occur without causing improper operation of the relay. 80

Although I have herein shown and described only one form of railway traffic controlling apparatus embodying my invention, it is understood that various changes and modifications may be made therein within the scope of the appended claims without departing from the spirit and scope of my invention. 85

Having thus described my invention, what I claim is:

1. In combination, a relay comprising two magnets, means for alternately energizing said magnets in such manner that the two magnets are energized for different proportions of a given interval of time, and a member constrained to occupy a first or a second position depending upon which magnet is energized for the larger proportion of such time interval. 90

2. In combination, a relay comprising two magnets, means for alternately energizing said magnets in such manner that the two magnets are energized for different proportions of a given interval of time, and a member controlled by said magnets in accordance with the relative proportions of said time interval during which said magnets are energized. 100

3. Railway traffic controlling apparatus comprising a train carried relay comprising two magnets, means for alternately energizing said magnets in such manner that the two magnets are energized for different proportions of a given interval of time, a member constrained to occupy a first or a second position depending upon which magnet is energized for the larger proportion of such time interval, and governing means on the train responsive to the position of said member. 110

4. Railway traffic controlling apparatus comprising a train carried relay comprising two magnets, means located partly in the trackway for alternately energizing said magnets in such manner that the two magnets are energized for different proportions of a given interval of time, a member controlled by said magnets in accordance with the relative proportions of said time interval during which the magnets are energized. 120

gized, and governing means controlled by said member.

5. Railway traffic controlling apparatus comprising a train carried relay comprising two magnets, means located partly in the trackway for alternately energizing said magnets in such manner that the two magnets are energized for different proportions of a given interval of time, a member con-

10 trolled by said magnets in accordance with the relative proportions of said time interval during which the magnets are energized, contacts controlled by said member, and governing means controlled by said contacts.

15 6. In combination, a relay comprising two magnetizable cores each provided with a sleeve of conducting material, two windings one on each said core, means for alternately energizing said windings in such

20 manner that one winding is energized for a larger proportion of a given interval of time than the other, and a member controlled by the magnetic fluxes in said cores in accordance with the relative proportions of said 25 time interval that said windings are energized.

7. In combination a relay comprising two magnets each comprising a magnetizable core provided with a conducting sleeve and 30 a winding, means for alternately energizing said windings in such manner that the two windings are energized for different proportions of a given interval of time, and a pivoted armature attracted by one or the other 35 of said magnets in accordance with the relative proportions of said time interval during which said windings are energized.

8. In combination, a relay comprising two 40 magnets each comprising a magnetizable core provided with a conducting sleeve and a winding, means for alternately energizing said windings in such manner that the two windings are energized for different proportions of a given interval of time, a pivoted 45 armature attracted by one or the other of said magnets in accordance with the relative proportions of said time interval during which said windings are energized, and a second armature controlled by only one of 50 said magnets.

9. In combination, a relay comprising two 55 magnets each comprising a magnetizable core provided with a conducting sleeve and a winding, means for alternately energizing said windings in such manner that the two windings are energized for different proportions of a given interval of time, a pivoted armature attracted by one or the other of said magnets in accordance with the relative 60 proportions of said time interval during which said windings are energized, a second armature controlled solely by one of said magnets, and a third armature controlled solely by the remaining magnet.

65 10. A relay comprising two pairs of cores

each provided with a conducting sleeve, a first winding comprising two coils one on each core of one pair, a second winding comprising two coils one on each core of the other pair, a pivoted armature responsive to flux in both pairs of cores, and two other pivoted armatures separately responsive to the fluxes in said pairs of cores, respectively.

11. A relay comprising two pairs of cores 70 each provided with a conducting sleeve, a first winding comprising two coils one on each core of one pair, a second winding comprising two coils one on each core of the other pair, a pivoted armature responsive to flux in both pairs of cores, two other pivoted armatures separately responsive to the fluxes in said pairs of cores respectively, and a contact controlled by each said armature.

12. In combination, a relay comprising 80 two pairs of cores each provided with a conducting sleeve, a first winding comprising two coils one on each core of one pair, a second winding comprising two coils one on each core of the other pair, means for alternately energizing said windings in such manner that the two windings are energized for different proportions of a given interval of time, a first armature controlled in accordance with the relative proportions of said 90 interval of time that said windings are energized, and two other armatures one controlled by each pair of cores and each responsive only to the flux in the associated cores.

13. Railway traffic controlling apparatus comprising a train carried relay having two slow acting magnets, means located partly in the trackway for at times energizing said 100 magnets alternately in such manner that the magnets are energized for different proportions of a given interval of time, a first armature controlled jointly by said magnets in accordance with the proportion of said 105 time interval that each magnet is energized, and a second armature controlled solely by one said magnet.

14. Railway traffic controlling apparatus comprising a train carried relay having two slow acting magnets, means located partly in the trackway for at times energizing said magnets alternately in such manner that the magnets are energized for different proportions of a given interval of time, a first armature controlled jointly by said magnets in accordance with the proportion of said 110 time interval that each magnet is energized, a second armature controlled solely by one said magnet, and governing means controlled by said two armatures.

15. Railway traffic controlling apparatus comprising a train carried relay having two slow acting magnets, means located partly in the trackway for at times energizing said 120 magnets alternately in such manner that the

- magnets are energized for different proportions of a given interval of time, first armature controlled jointly by said magnets in accordance with the proportion of said time interval that each magnet is energized, a second armature controlled solely by one said magnet, two contacts one controlled by each said armature, and governing means controlled by said two contacts.
- 10 16. Railway traffic controlling apparatus comprising a train carried relay having two slow acting magnets, means located partly in the trackway for at times energizing said magnets alternately in such manner that the magnets are energized for different proportions of a given interval of time, a first armature controlled jointly by said magnets in accordance with the proportion of said time interval that each magnet is energized, a second armature controlled solely by one said magnet, and a third armature controlled solely by the other magnet.
- 15 17. Railway traffic controlling apparatus comprising a train carried relay having two slow acting magnets, means located partly in the trackway for at times energizing said magnets alternately in such manner that the magnets are energized for different proportions of a given interval of time, a first armature controlled jointly by said magnets in accordance with the proportion of said time interval that each magnet is energized, a second armature controlled solely by one said magnet, a third armature controlled solely by the other magnet, and governing means controlled by said armatures.
- 20 18. Railway traffic controlling apparatus comprising a first train carried relay, means located partly in the trackway for at times energizing said first relay intermittently in such manner that the periods of energization and de-energization of said first relay occupy different proportions of a given interval of time, a second relay on the train comprising two slow acting magnets, means controlled by said first relay for energizing said two magnets alternately, and governing means controlled by said two magnets in accordance with the relative proportions of a given interval of time that the magnets are energized.
- 25 19. Railway traffic controlling apparatus comprising a first train carried relay, means located partly in the trackway for at times energizing said first relay intermittently in such manner that the periods of energization and de-energization of said first relay occupy different proportions of a given interval of time, a second relay on the train comprising two slow acting magnets, a circuit for one of said magnets including a front contact of said first relay, a circuit for the remaining magnet including a back contact of said first relay, and governing means controlled by said second relay in accordance with the relative proportions of a time interval that said magnets are energized.
- 30 20. Railway traffic controlling apparatus comprising a first train carried relay, means located partly in the trackway for at times energizing said first relay intermittently in such manner that the periods of energization and de-energization of said first relay occupy different proportions of a given interval of time, a second relay on the train comprising two slow acting magnets, means controlled by said first relay for energizing said two magnets alternately, a first armature controlled jointly by said magnets in accordance with the relative proportions of a time interval that the magnets are energized, a second armature controlled solely by one of said magnets, a third armature controlled solely by the remaining magnet, and governing means controlled by said three armatures.
- 35 21. Railway traffic controlling apparatus comprising a first train carried relay, means located partly in the trackway for at times energizing said first relay intermittently in such manner that the periods of energization and de-energization of said first relay occupy different proportions of a given interval of time, a second relay on the train comprising two slow acting magnets, a circuit for one of said magnets including a front contact of said first relay, a circuit for the remaining magnet including a back contact of said first relay, an armature controlled jointly by said magnets in accordance with the relative proportions of a time interval that the magnets are energized, two contacts responsive to continuous or intermittent energization of said two magnets respectively, and governing means controlled by said armature and by said contacts.
- 40 22. Railway traffic controlling apparatus comprising a train carried relay having two slow acting magnets, means located partly in the trackway for at times energizing said magnets alternately in such manner that the magnets are energized for different proportions of a given interval of time, a first armature controlled jointly by said magnets in accordance with the proportion of said time interval that each magnet is energized, and a second armature controlled solely by one said magnet, a third armature controlled solely by the other magnet, governing means controlled jointly by said three armatures, and other governing means controlled by said second and third armatures but not by said first armature.
- 45 23. In combination, a relay comprising two magnets, means for at times energizing said magnets alternately in such manner that the two magnets are energized for different proportions of a given interval of time, means for at other times energizing

one or the other of said magnets continuously, a first armature controlled in accordance with the relative proportions of said interval of time that said magnets are energized, two other armatures controlled by said magnets respectively, and governing means controlled by said three armatures.

24. In combination, a relay comprising two magnets, means for at times energizing 10 said magnets alternately in such manner that the two magnets are energized for different proportions of a given interval of

time, means for at other times energizing one or the other of said magnets continuously, a first contact controlled solely by one 15 of said magnets, a second contact controlled solely by the other magnet, and a third contact controlled jointly by the two magnets in accordance with the relative proportions of said interval of time that the magnets are 20 energized.

In testimony whereof I affix my signature.

HAROLD O. HOLTE.
